METHOD AND APPARATUS FOR CONTROLLING REFRACTORY LINED FURNACE TEMPERATURES

William B. Lane, Los Gatos, Calif.

Application November 17, 1953, Serial No. 392,775

2 Claims. (Cl. 250—83)

(Granted under Title 35, U. S. Code (1952), sec. 266)

The invention described herein may be manufactured and used by or for the Government of the United States of America for governmental purposes without the payment of any royalties thereon or therefor.

This invention relates to furnaces and, more particularly, to means for controlling furnace temperatures.

The ability to closely control temperatures in high-temperature smelting or melting furnaces has been a constant challenge and many efforts have been made at providing improved temperature indicating and control means such as pyrometers. As is well known, any furnace installation has a theoretically optimum operating temperature which depends upon its design, the intended furnace practice, and other factors, this optimum, however, being a compromise or balance between the maintenance of a high production rate on the one hand and the economic necessity of prolonging the furnace roof refractory on the other. Obviously, high temperatures produce faster reactions, but, at the same time, the desire for such reactions must be tempered by the fact that excessively intense heats produce a refractory lining "sweating" during which the refractory spalls or wears at such a wasteful rate as to very materially reduce the life or campaign for which the refractory brick is intended. Such wear, of course, necessitates furnace shut-downs for repairs which are so expensive and time-taking as to render the whole operation uneconomical.

As stated, the importance of heat control has led to the development and adoption of such instruments as pyrometers or, when these are not available, it has placed a premium on the services of experienced furnace men who are able to judge temperatures by observing color. Pyrometers, however, have not provided an entirely suitable answer and this has been due primarily to their unreliability in the presence of smoke or flame and the difficulty of correcting for emissivity of different materials. Further, the critical factor to be controlled is not so much the temperature as it is the actual quantity or amount of brick wear or spall and, obviously, the wear of different bricks will vary considerably, particularly when subjected to varying furnace practices. Consequently, direct temperature readings, even if exact, do not provide precise data for spall control and, since each heat introduces some varying factors, it becomes very possible for a theoretically optimum temperature to be found inappropriate and uneconomical in practice. Of course, visual temperature determinations also are subject to this criticism and, in addition, control by such a method is, at best, simply an estimate or an opinion which, most certainly, is non-quantitative insofar as refractory wear is concerned.

It is, therefore, an object of the present invention to provide a manner of controlling a furnace temperature which is based directly upon the amount of wear as opposed to temperature readings.

A further object is to provide means operative during a furnace heat for selectively and periodically determin-

2

ing wear at different locations of the furnace by obtaining readings from the spall emanating from those particular locations.

Still another object is to provide means for continuously controlling furnace temperatures in accordance with the quantitative amount of spall emanating from a selected location in the furnace.

According to the invention refractory wear is quantitatively determined by incorporating a radioactive isotope in portions of the refractory lining of the furnace. Such portions then spall or wear at the same rate as the remaining refractory with the result that such spall as is carried into the slag will contain a certain quantity of the radioactive isotope which, when exposed to suitable counting instruments, such as a Berkeley scaler with a Geiger tube, will provide an accurate record of the actual amount of refractory spall occurring during the period in question. Preferably, the isotope is incorporated in selected bricks of the refractory wall so that the reading will be representative of conditions throughout the furnace. Also, if desired, it is possible to incorporate isotopes of differing self-identifying counting energies at different critical locations of the furnace and readings then can provide selective data for these separate locations.

As to these readings, one phase of the invention contemplates a periodic ladling of slag samples which then are carried to a counter for testing, while another modification provides a continuous record made from a particular isotope whose presence can be determined and counted while in the slag bath. Such an isotope can be a gas-evolver in which case the gas can be conducted to a counter, or it can be an isotope with an emission different from that in the ladled testing. In this latter event, the ladled isotopes may be beta emitters while the isotopes for the continuous record may be a gamma emitter. The continuous counter in this arrangement would accept and record only gamma ray energy counts. In the preferred form of the invention, both the continuous reading and the sampling procedures are used.

The invention is illustrated in the accompanying drawings of which Fig. 1 is a longitudinal section through an open hearth furnace, and Fig. 2 a vertical section along lines II—II of Fig. 1.

The furnace illustrated in the drawings represents a conventional open-hearth type provided with a customary hearth 1 formed of layers of silica sand 2, fire clay 3 and burned chrome 4, this hearth forming a bed on which a bath 6 of molten metal and slag is subjected to open flame coming from burners 7. For purposes of understanding the invention, very little of the actual furnace structure is involved, the only portions of present interest being a furnace roof 8 formed for the most part of refractory bricks, a rear wall 9 and a front wall 11 in which is mounted a charging door 12. These portions generally can be referred to as "overhead" portions to connote the fact that they lie above the furnace bath. Consequently, as might be surmised, the present invention is by no means limited to open hearth practices since, in fact, the present teachings can be applied to any furnace which operates at sufficiently high temperatures to spall the refractories.

As previously indicated, one of the important features of the present invention resides in incorporating a radioactive isotope in the furnace lining so that spalling of this lining will carry the isotope into the slag bath. As shown, the refractory lining includes roof 8 which is formed of a number of conventional refractory bricks 13 among which are interspersed, at selected locations, a plurality of bricks 14 in which the radioactive isotope has been combined. Most suitably, bricks 14 are strategically located about the roof to assure that repre-

sentative amounts of the isotopes are carried into the spall from all critical locations within the furnace. Usually, for instance, the temperature variations are greatest transversely of the furnace so that, as shown in the drawings, it is desirable to mount bricks 14 in transverse rows of three spaced longitudinally along the roof. With such an arrangement, when the furnace is brought up to melting heat, the refractory lining commenced to spall and the spall from bricks 14 drops into slag 6 where it is mixed thoroughly due to the roiling motion of the bath. However, the mixture will be representative of conditions throughout the furnace and determinations of roof wear can be made by taking a sample of the slag and subjecting it to a radiation counter of any suitable type.

As to the particular isotope used, this may be any which is consistent with the furnace practice of the particular installation being equipped, although, preferably, the isotope may be chosen for its availability, cheapness and radiological properties. By way of example, a refractory lining may be formed by incorporating about 50 millicuries of Sr⁸⁹ in each brick 14, although the amount incorporated in the brick may vary with furnace design and capacity. The present example assumes a 150-ton open-hearth furnace to which the following conditions are assigned: (a) a slag burden of 15,000 pounds; (b) a basic bottom and practice; (c) a normal roof life of 200 heats, and (d) a 90% brick usage before roof failure. Sr⁸⁹ is an isotope which would be consistent with the melting practice represented by such a furnace, although other isotopes having differing chemical properties of oxidation, reduction and volatilization also could be substituted providing they are consistent with the melting practice to which they will be subjected. In forming the Sr⁸⁹ bricks, the 50 millicuries of Sr⁸⁹ is thoroughly mixed with the raw material and the brick then may be mounted in the roof of the furnace in the manner shown and at any desired time during the heat, a 10 gram sample of slag may be extracted by a ladle and subjected to the counter instrument. Of course, excessive refractory wear or spall will be indicated by the high count of the instrument and, if such is found to exist, the furnace temperature can be reduced. Low counts will indicate the desirability of increasing the furnace temperature, and, as would be expected, the counts can be checked against calculated data obtained by quantitative testing under known conditions.

Another practice which, for certain installations, may have some advantage over that just described is illustrated in Fig. 2. Briefly, this practice contemplates the use of radioactive bricks 14a, 14b and 14c, each of which is formed with an isotope having a counting energy that is different from that of the others so that these isotopes each are self-identifying in the slag bath example. The obvious purpose of this modification is to permit determinations of wear at selected locations of the furnace lining and for this reason these isotopes, most suitably, are included one in each of the three bricks of the transverse rows because, as explained, temperature variations are greatest between the sides and the center. Such differing isotopes are well known and include Y⁹¹, Nb⁹⁵, Zr⁹⁵ and many others. Of course, the slag bath always is in a constant state of flux and movement so that the spall from these bricks is evenly mixed but, nevertheless, such counting mechanism as is commercially available is capable of distinguishing the separate counting energies of the spall from each of these bricks.

Another feature of the invention resides in providing a means for continuously determining refractory wear and this continuously operating means may supplement the intermittent sampling procedure permitted by bricks 14. Such a continuous reading is made possible by mounting a counting instrument 16 in a suitable position in a furnace wall, such as rear wall 9, at approximately the longitudinal position of what is known as the No. 3 door

of a conventional open-hearth furnace. This particular location of the furnace is frequently the point at which the furnace heat becomes most intense so that the incorporation of the counter at this position serves as a means for maintaining the entire furnace temperature below a level that is known to be excessive. Counter 16, as will be noted, is provided with a customary column 17 which is aligned with a point 18 on the furnace hearth or in the slag bath as the case may be. The counter, in turn, is actuated by energy contained in spall dripping from another brick 19 mounted in furnace roof 8 and brick 19, as will be noted is mounted in the roof directly above point 18, so that spall from this brick is immediately sighted by column 17 of the counter.

When using such a continuous reading in conjunction with the intermittent sampling outlined from the spall of bricks 14, it is necessary to form brick 19 of an isotope which can be distinguished from the isotopes used for these other bricks. For this purpose, the isotope of brick 19 may be Cs¹³⁷ which, as is known, is a gamma ray emitter as opposed to Sr⁸⁹ which is a beta ray emitter. Brick 19 may be formed in the same manner as the other bricks and it has been noted that the incorporation of isotopes in these bricks in no way affects the normal spalling rate of the bricks or their strength or refractory capacity. If desired, it is possible to dispense with the necessity of mounting a counter in the wall of the furnace and this may be accomplished by incorporating an isotope in brick 19 which, when subjected to the heat of a bath evolves a gas that then may be taken out of the furnace through any discharge opening and conducted to a counter which may be located at any desired convenient and protected position.

With a refractory lining formed as described above, it has been further possible to determine with an unusual degree of precision the exact amount of lining wear and, based upon such determination, it is possible to vary the furnace temperatures so as to prolong the roof life to a maximum extent consistent with a desired production rate. If desired, suitable mechanism can be combined with counter 16 so that the continuous count can be utilized to actuate an audible or visual signal when the temperature exceeds a desired degree. As another possibility which should require no more than ordinary skill, counter 16 can be used to actuate control mechanism for automatically increasing or decreasing temperatures.

The principal advantage of the present invention lies in the fact that the wear determinations are made directly from the quantitative amount of wear or spall and, consequently, the necessity of relating wear to observations made by pyrometers or by the human eye is eliminated. Further, the use of the radioactive isotopes completely avoids errors produced by the presence of smoke, etc. which sometimes has very seriously affected operations controlled by pyrometric means.

Obviously many modifications and variations of the present invention are possible in the light of the above teachings. It is therefore to be understood that within the scope of the appended claims the invention may be practiced otherwise than as specifically described.

I claim:

1. A method of controlling refractory lining wear of a furnace, comprising aligning a radioactive energy counter with a selected position in the furnace slag bath, incorporating a radioactive isotope of a certain ray emanation in said refractory lining above said selected position, incorporating different ray-emitting radioactive isotopes of mutually differing self-identifying counting energies in other selected locations of said refractory lining, controlling temperature conditions in accordance with readings of said aligned counter, and determining wear in said other selected locations by readings obtained from slag bath samples.

2. A method of controlling temperature conditions of a refractory-lined furnace, comprising rendering an over-

5

head portion of said refractory lining radioactive, applying furnace heat in sufficient amounts for producing spall drop, counting the radioactive energy present in said spall drop, and regulating said heat application in accordance with said count.
